UNITED STATES PATENT OFFICE

FREDERICK K. FILDIES, OF ALTOONA, PENNSYLVANIA

SHIPPING CONTAINER

Application filed January 23, 1931. Serial No. 510,667.

This invention relates to shipping containers such as are used in making shipments in separate consignments by railroad, and which are separately removable from special cars designed to support them in transit.

Containers of the type referred to are ordinarily constructed with sheet metal top, side and end walls; and it has been the practice heretofore to connect these side walls, top and end walls by angle strips which extend continuously around their perimetric edges meeting at opposite ends of the structures. The bending of these continuous binding strips into conformity with the upper corners of the container was extremely difficult of accomplishment in view of the sharpness of the angle and often precluded the formation of weathertight junctures.

One object of my invention is to overcome the above indicated drawbacks through use of separate horizontal and vertical strips terminating short of the upper corners of the containers, and through provision of corner pieces to connect the container walls in the intervals between the separate binding strips aforesaid.

In addition to the foregoing, I aim to embody in the corner pieces, hooks for engagement by lifting tackle incident to placement and removal of the containers with respect to the supporting cars.

Other objects and attendant advantages of this invention will be manifest from the detailed description following in connection with the attached drawing, whereof Fig. I is a view showing, in side elevation, a fragmentary portion of a shipping container embodying the present improvements.

Fig. II is a corresponding fragmentary end elevation of the structure.

Figs. III and IV are detail sectional views taken as indicated respectively by the arrows III-III and IV-IV in Fig. II.

With more detailed reference to these illustrations, the top or roof of the container is designated by the numeral 5, one of its side walls at 6, and one of its end walls at 7, these being all of sheet metal. In the present instance, the top 5 is arched; while the end 7 is appropriately profiled to conform with the

curvature of the top. The lateral edges of the top 5 are bent downwardly as at 9 to meet the side wall 6 at which region the two are backed up by a reinforcing longitudinal 8 and joined together permanently with rivets 10. Instead of the top, side walls, and end walls 5-7 of the structure being connected, as ordinarily, by a continuous angle binding strip, a separate horizontal binding strip 11 is here employed at each end of the structure to connect the top with the end wall, and separate vertical binding strips, whereof one is indicated at 12, to connect each side wall with the end wall, the said separate strips terminating short of the upper corner of the container. In accordance with preferred practice, rivets 13 are used as a means for permanently securing the separate binding strips 11 and 12 with interposition of suitable sheet material 14 between them, and backing strips 15 along each line of the rivets to predetermine weathertight junctures.

For the purpose of connecting the top 5, side 6, and end wall 7 in the interval between the contiguous ends of the binding strips 11 and 12 at each upper corner of the receptacle, I provide a cast corner piece 16 of right angle cross section. It is to be particularly noted that the extremities of the corner piece are recessed as at 17 and 18 for capacity to lap the ends of the binding strips 11 and 12. To insure weather tightness, strip packing 19 (Figs. II and III) is placed between the corner piece and the overlapped areas of the container walls, the packing backed by washer plates 20 and all secured together with rivets 21.

To dispense with the necessity for separately attached hooks for engagement by the lifting tackle employed in handling the container, I integrally form each corner piece with a hook such as shown at 22, the said hook being suitably reinforced by vertical and horizontal webbing at 23 and 24.

In addition to the attributes already pointed out, my invention greatly facilitates assembling of the various parts that enter into the construction of shipping containers, and it moreover affords a sturdy corner construction capable of withstanding rough usage.

with insurance against the development of open seams at the designated region.

While I have described a particular corner construction representing one embodiment of my invention in a shipping container, it will be apparent that various changes may be made in the specific form of binding strips and corner pieces herein disclosed without departing from the spirit of the invention; and 10 it will be further understood that in using the term "hook", I mean to include any like form of securing means adapted for engagement by lifting tackle.

Having thus described my invention, I 15 claim:

1. A shipping container of the character described having side walls, top and end walls of sheet metal, separate horizontal and vertical binding strips terminating short of the 20 upper corners of the container and connecting its top and side walls with the end walls and corner pieces continuous with the horizontal and vertical binding strips aforesaid, connecting the top, side and end walls of the 25 container and completely filling in the intervals between the binding strips, the said corner pieces being integrally formed with hooks for engagement by lifting tackle.

2. A shipping container of the character 30 described having side walls, top and end walls of sheet metal; separate horizontal and vertical binding strips terminating short of the upper corners of the container and respectively connecting the top and side walls 35 with the end walls; and angle pieces connecting the top, side walls and end walls of the container in the intervals between the binding strips, the said corner pieces overlapping the ends of the binding strips and being 40 formed with hooks for engagement by lifting tackle.

3. A shipping container of the character 45 described having side walls, top and end walls of sheet metal; separate horizontal and vertical angle binding strips terminating short of the upper corners of the container and connecting its top and side walls with the end walls; and corner pieces continuous with the 50 horizontal and vertical binding strips aforesaid, also of angle section connecting the top, side and end walls of the container and completely filling in the intervals between the binding strips, the said corner pieces being 55 integrally formed with hooks for engagement by lifting tackle.

4. A shipping container of the character 60 described having side walls, top and end walls of sheet metal; separate horizontal and vertical angle binding strips terminating short of the upper corners of the container and respectively connecting the top and the side walls with the end walls; and corner pieces also of angle section connecting the 65 top, side walls and end walls of the container in the intervals between the binding strips,

the said corner pieces overlapping the ends of the binding strips and being formed with hooks for engagement by lifting tackle.

In testimony whereof, I have hereunto signed my name at Altoona, Pennsylvania, 70 this 19th day of January, 1931.

FREDERICK K. FILDES.
